UNITED STATES PATENT OFFICE.

WILLIAM A. TROUT, OF LOS ANGELES, CALIFORNIA, ASSIGNOR TO EMSCO STEEL PRODUCTS COMPANY, A CORPORATION OF CALIFORNIA.

DERRICK CONSTRUCTION.

Application filed November 20, 1923. Serial No. 675,795.

To all whom it may concern:

Be it known that I, WILLIAM A. TROUT, a citizen of the United States, residing at Los Angeles, in the county of Los Angeles, State 5 of California, have invented a new and useful Derrick Construction, of which the following is a specification.

This invention relates to well drilling equipment and relates particularly to derricks of the type used in the petroleum oil 10 producing industries.

In the rotary system of well drilling, the hole is formed by use of rotary tool driven by a vertical shaft formed of consecutive 15 lengths of drill pipe, this drilling shaft or string of drill pipe, as it is called, is rotated from the derrick floor by use of rotary drive mechanism. The string of drill pipe is supported by the derrick through the use of 20 block and tackle, and the weight thereof which must be supported by the derrick structure is often quite large and in many instances exceeds the safe stresses for which 25 the derrick was originally designed. This is particularly true when the hole being drilled ranges between 3000 or 4000 feet in depth, as often occurs.

After the drilling operations are completed the only strains placed upon the derrick are those of handling well tubing and such lifting as required in the attendance of a pumping well. It will be recognized that the stresses placed on the derrick after 30 the completion of drilling are comparatively small so that the capacity of the derrick is not approached at any time after the drilling has been completed.

It is an object of the invention to provide a derrick having permanent legs and structure 40 suitable to take care of the ordinary stresses and also having auxiliary supporting members arranged for use during the drilling operation so that the strength of the derrick is ample to care for the strains incurred due to the supporting of great 45 lengths of drill pipe, which auxiliary members may be quickly removed after the drilling operation has been completed, thus leaving a derrick structure which is ample for 50 a pumping or producing well.

It is a further object of the invention to provide securement means whereby the auxiliary members may be conveniently secured and quickly detachable without excessive expenditure of time and labor.

It is a further object of the invention to provide a derrick having a novel tubular and structural combination in the design of the legs thereof, thus producing marked 60 rigidity and resistance.

The especial advantages of the invention and further objects thereof will be made evident hereinafter.

Referring to the drawing which is for illustrative purposes only:

Fig. 1 is a fragmentary horizontal section illustrating my improved derrick construction.

Fig. 2 is a fragmentary elevation taken as indicated by the arrow 2 of Fig. 1.

Fig. 3 is an enlarged section showing the securement and spacing means employed in the practice of the invention.

Fig. 4 is a diagrammatic plan view of a derrick floor showing the arrangement of 75 primary angle iron derrick members and the relative arrangement of tubular secondary members.

As shown in the drawing, the derrick is usually constructed of four legs 11 placed in 80 the arrangement shown in Fig. 4. These legs extend substantially vertically, but converge, as they progress upwardly, in pyramid form. The primary legs 11 are tied together at regular intervals by girts 12 and 85 diagonal struts 13, both of which preferably consist of structural angles, such members 12 and 13 being secured to the primary legs 11 by the use of gusset plates which bolt to the legs 15 of the members 11. Within the 90 V shaped opening or angular space between the legs 15 of each structural angle member constituting a leg 11, is placed an auxiliary or secondary leg member consisting of a pipe string 17. This pipe string consists of 95 a suitable number of standard pipe lengths secured together by collars 18 so that a continuous tubular member equal in length to one of the derrick legs is formed.

In the erection of a derrick, bolts and rivets are employed, the heads of which project on the inner faces of the angle members constituting the primary legs. The invention employs means whereby the secondary legs are secured to the primary legs but are 105 maintained in arrangement spaced slightly apart from the legs 15 so that clearance for the bolt heads and the collars 18 is provided. This spacing means is in the form of a flat bar 20 bent on a curvature at 21 substan- 110

tially the same as the circumference of the pipe 17 and having the ends 22 and 23 thereof extending tangentially at right angles to each other so as to fit against the inner faces of the legs. Strap bolts 25 are provided which consist of round stock centrally flattened and having the ends 27 thereof left cylindrical and threaded so that nuts 30 may be screwed thereon when the ends 27 are extended through holes 32 and 33 in the members 11 and the spacers 20. The spacers 20 are distributed along the secondary leg member 17 in proper spacing to produce the binding of the primary and secondary members together so that they will act integrally in absorbing the strain caused by the placing of loads on the derrick.

When the heavy work, such as the drilling of the well, has been completed and the well 20 has been placed in production, the secondary leg member 17 may be removed by releasing the nuts 30 and may then be used for other purposes as piping, or for the support of other derricks. It will be readily recognized that the saving in construction attained in this manner amounts to considerable as the material which may be temporarily employed and then removed for transfer to other operations will amount to 400 feet 30 of pipe in a 100 foot derrick. We believe that the economy, and therefore the value of a transformable derrick of this character will be immediately evident.

I claim as my invention:

35 1. In a derrick, the combination of: primary angle iron leg members joined in a derrick structure; secondary leg members consisting of lengths of pipe coupled together in continuous arrangement and secured in the V's of said angle iron leg members, for reinforcing said primary members during heavy duty; and spacing members disposed between said secondary members and the faces of said V's.

45 2. In a derrick, the combination of: angle iron leg members suitably joined in a derrick structure; secondary leg members consisting of lengths of pipe secured together in continuous arrangement for reinforcing said primary leg members during heavy duty; and means removably securing said secondary members in the V's of said angle iron members.

55 3. In a derrick, the combination of: angle iron leg members suitably joined in a derrick structure; secondary leg members consisting of lengths of pipe for reinforcing said primary leg members during heavy duty; and means removably securing said

secondary members in the V's of said angle iron members in positions spaced apart sufficiently from said angle iron members to allow clearance for couplings of said pipe.

4. In a derrick, the combination of: angle iron leg members suitably joined in a derrick structure; secondary leg members consisting of lengths of pipe secured together in continuous arrangement by couplings for reinforcing said primary leg members during heavy duty; means removably securing said secondary members in the V's of said angle iron members; and bar members between said secondary members and the V faces of said primary leg members for spacing said secondary members apart from said primary members to provide clearance for the coupling members of said pipe and for means employed to secure said primary members.

5. In a derrick, the combination of: angle iron leg members suitably joined in a derrick structure; and tubular reinforcing members extending in the V's of said angle iron leg members.

6. In a derrick, the combination of: angle iron leg members suitably joined in a derrick structure; secondary leg members consisting of lengths of pipe secured together in continuous arrangement by couplings for reinforcing said primary leg members during heavy duty; means removably securing said secondary members in the V's of said angle iron members; and bar members between said secondary members and the V faces of said primary leg members for spacing said secondary members apart from said primary members to provide clearance for the coupling members of said pipe and for means employed to secure said primary members, said means removably securing said secondary members consisting of a strap of quarter circular curvature having threaded portions on the ends thereof which extend at substantially right angles to each other, and said bar members consisting of a quarter circular curved portion bent to the radius of the secondary pipes and having the ends thereof extending perpendicularly so as to rest against the inner faces of the angle iron primary legs, and being equipped with holes in the ends thereof through which the threaded portions of said securing means are extended.

In testimony whereof, I have hereunto set my hand at Los Angeles, California, this 1st day of November, 1923.

WILLIAM A. TROUT.
